UNITED STATES PATENT OFFICE.

THOMAS CROSTON, OF HOQUIAM, WASHINGTON.

ROTARY ENGINE.

SPECIFICATION forming part of Letters Patent No. 674,258, dated May 14, 1901.

Application filed March 16, 1900. Serial No. 8,953. (No model.)

To all whom it may concern:

Be it known that I, THOMAS CROSTON, a citizen of the United States, and a resident of Hoquiam, in the county of Chehalis and State 5 of Washington, have invented a new and Improved Rotary Engine, of which the following is a full, clear, and exact description.

The invention relates to rotary engines such as shown and described in the Letters Patent 10 of the United States No. 633,813, granted to me on September 26, 1899.

The object of the present invention is to provide a new and improved rotary engine capable of instantly and automatically adjusting itself to the requirements of the load and to the variation of steam-pressure, the engine being arranged to prevent racing under any circumstances and is not liable to slow down until the limit of the working power of 20 the engine is reached, and is constructed to permit of utilizing the motive agent to the fullest advantage, with a variation in the cut-off from zero to full revolution, and to allow of convenient reversing, and to allow the engineer 25 to ascertain the horse-power under which the engine is running.

The invention consists of novel features and parts and combinations of the same, as will be fully described hereinafter and then 30 pointed out in the claims.

A practical embodiment of my invention is represented in the accompanying drawings, forming a part of this specification, in which similar characters of reference indicate corresponding parts in all the views.

Figure 1 is a sectional side elevation of the improvement. Fig. 2 is a section of the governing-engine, the section being on the line 2 2 in Fig. 1. Fig. 3 is a transverse section 40 of the main rotary engine, the section being on the line 3 3 in Fig. 1. Fig. 4 is a like view of the improvement on the line 4 4 in Fig. 1. Fig. 5 is an enlarged transverse section of the governing-engine, the section being on the line 5 5 in Fig. 1. Fig. 6 is similar view of the same on the line 6 6 in Fig. 1. Fig. 7 is an enlarged sectional plan view of the same on the line 7 7 in Fig. 1. Fig. 8 is a transverse section of the main rotary engine, the section being on the line 8 8 in Fig. 1. Fig. 9 is a sectional side elevation of the abutment-packings. Fig. 10 is a plan view of part of

the same. Fig. 11 is a perspective view of the abutment-packing, showing the pairs of blocks separated and the blocks of each pair 55 partially separated; and Fig. 12 is a perspective view of a pair of said blocks.

The improved rotary engine consists, essentially, of a main rotary engine A and an auxiliary or governing rotary engine A', of 60 which the latter is essentially of the construction shown in the patent above referred to. The engines A A' are provided with cylinders A² A³, respectively, having heads A⁴ A⁵ and A⁶ A⁷, respectively, and abutment portions 65 A⁸ A⁹, containing packings B B', respectively, engaging the peripheral surfaces of the cylindrical pistons C C', of which the piston C is arranged on the main shaft D, while the piston C' of the governing-engine is mounted loosely 70 on a shaft D' and has a yielding connection with the same, as hereinafter more fully described, to govern the admission of steam to the cylinder A³, according to the load, by way of the shaft D'. The shaft D' carries the 75 main admission-valve E in the steam-chest F for the main rotary engine A, and the yielding connection referred to between the piston C' and the shaft D' controls the cut-off valve 80 E', arranged above the admission-valve E, likewise located in the steam-chest F, as is plainly shown in Figs. 1 and 3. A supply-pipe F' opens into the upper end of the steam-chest F and is connected with a suitable 85 source of steam-supply, and a branch pipe F² leads from the pipe F' and opens into the cylinder A³ between the head A⁷ and the adjacent face of the piston C', the same as in the patent above mentioned.

The shaft D' is directly geared to the main 90 shaft D and is for this purpose provided at one end with a bevel gear-wheel D², meshing with a bevel gear-wheel D³, secured on a shaft D⁴, carrying at its lower end a bevel gear-wheel D⁵, in mesh with a bevel gear-wheel 95 D⁶, secured on the main driving-shaft D. The gearing described is so proportioned that the shaft D' makes one-half a revolution to one full revolution of the shaft D.

The upper or cut-off valve E' is rotated from 100 the governing-engine A' according to the difference in the rotary motion of the piston C' and the shaft D', and for this purpose the following arrangement is made: On the shaft

D' inside the cylinder-head A⁶ is secured a head G, on which are mounted to rotate pinions G', in mesh at one side with a bevel gear-wheel G², held on a hub G³, attached to a transverse bar G⁴, secured to the inner face of the piston C', as is plainly shown in Figs. 1, 5, and 7, so that the rotary motion of the piston C' in the cylinder A³ causes a like rotary motion of the gear-wheel G². The opposite sides of the pinions G' are in mesh with a bevel gear-wheel G⁵, secured on the face of a spur-wheel G⁶, mounted to rotate loosely on the shaft D' inside of the head A⁶, (see Figs. 1, 5, and 7,) and said spur-wheel G⁶ is in mesh with a like spur-wheel G⁷, secured on one end of the shaft E², on which the upper cut-off valve E' is fastened, said shaft E² being journaled in suitable bearings in the chest F and the head A⁶ of the auxiliary or governing engine A'. The valve E' is cylindrical and is formed with two ports a a', standing at right angles to each other, as is plainly shown in Figs. 1 and 3, and similar ports b b' are formed in the lower valve E. The lower half of the upper valve E' is mounted to turn in a suitable seat in the steam-chest F, and the upper portion of said valve extends into a chamber F³, into which passes the motive agent from the supply-pipe F'. The lower ends of the ports a a' are adapted to open into a channel F⁴, formed in the steam-chest F and leading to the upper end of the ports b b' in the valve E, which latter is mounted to rotate completely in a seat formed in the steam-chest F. The relation of the ports a a' to the ports b b' is such that when the port b' opens, the port a' closes, the port b opens, and port a closes. Now when the cut-off valve E' lags behind it is evident that the ports a and a' admit steam longer to the valve E, according to requirements. When the engines are set to run a certain number of revolutions in a time unit and any additional load is thrown on, then the yielding connection of the auxiliary engine A' operates to keep up the speed by turning the valve E' accordingly, and when the load is thrown off the valve E' is likewise actuated from the yielding connection to keep the engine from racing. The lower ends of the ports b b' are adapted to discharge the steam into a chamber F⁵, connected by ports c c' with the interior of the cylinder A² at opposite sides of the abutment B, as is plainly indicated in Fig. 3. The ports c c' at the chamber F⁵ are controlled by valves F⁶ F⁷, respectively, held on the ends of a lever F⁸, fulcrumed at its middle in the chamber F⁵, so that one of the ports is closed by its corresponding valve at the time the other port is open. Thus the port c or c' not used at the time as the admission-port for the motive agent is closed, while the other port is open. For instance, as shown in Fig. 3, the port c is closed and the port c' is open and is the admission-port for allowing the motive agent to pass into the cylinder A² at the right-hand side of the abutment B and act suc-

sively on the piston-heads H H' to rotate the piston C in the direction of the arrow d'.

The piston-heads H H' are mounted to slide diametrically opposite each other in the piston C and extend for this purpose in correspondingly-shaped openings C², each leading at its inner end to a chamber C³, containing a spring H², pressing against the inner end of the corresponding piston-head to insure an outward movement of the piston-head, so that the packing H⁴ in the piston-head contacts with the inner peripheral surface of the cylinder. The inner end of the edge of the piston-head H is provided with a flange H², fitting in the chamber C³ and abutting on the shoulder between the opening C² and the chamber C³, so that the outward movement of the piston-head is limited by the flange coming in contact with the shoulder, as will be readily understood by reference to Fig. 3, whereby only the packing H⁴ in the outer end of the piston is forced in contact with the peripheral surface of the cylinder. The inner end of each of the chambers C³ is connected by a port e with a chamber C⁴, connected by ports e' e² with the interior of the cylinder on opposite sides of the corresponding abutment, so that the motive agent on the pressure side of the piston-head can pass through the corresponding port into the chamber C⁴ and from the latter by the port e into the chamber C³ to press against the piston-head H and force the same outward until the flange H² abuts against the shoulder in the piston, thus relieving the packing H⁴ of any sudden jar when moving in contact with the inner surface of the cylinder and also preventing any more friction on the inner surface of the cylinder than that of the spring in the piston-head. The other port on the exhaust side of the piston-head H or H' is in communication with the outer air by way of the exhaust ports and valves, as hereinafter more fully described, and in order to close this port on the exhaust side of the piston-head valves C⁵ C⁶ are provided, held on a lever C⁷, fulcrumed at its middle in the chamber C³. Now when the several parts are in the position shown in Fig. 3 and motive agent passes into the cylinder A², then it can pass through the port e' for the piston-head H into the chamber C⁴ to force the valve c⁶ to its seat and close the port e², while the other valve c⁵ remains open. When the engine is reversed and the port c becomes the inlet-port, then the motive agent passes through the port e² into the chamber C⁴ to open the valve c⁶ and close the valve c⁵ on the port e', which latter is now on the exhaust side of the piston-head. The valves c⁵ and c⁶ thus control the motive agent to and from the chambers C³ C⁴ to cause the motive agent to press the piston-heads H H' outward and hold their shoulders H² against the piston, the valves also serving to prevent compression or vacuum in the said

chambers during the inward and outward sliding motion of the piston-heads.

The interior of the cylinder A² is adapted to connect by exhaust-ports f f' with ports f² f³, respectively, in the exhaust-valves J J', mounted to oscillate in suitable bearings formed on the outside of the cylinder A². (See Figs. 3 and 4.) The ports f² f³ are adapted to register with ports f⁴ f⁵, respectively, 5 formed in the lower portion of the cylinder-wall and connecting with an exhaust-port f⁶, leading to the outer air. The valves J J' are so arranged that when the port of one connects the interior of the cylinder with the 10 outer air by way of the exhaust-port f⁶, then the other valve is in a closed position. For instance, as shown in Fig. 3, the valve J is closed while the valve J' is open—that is, its port f³ connects with the ports f' and f⁵ to 15 connect the interior of the cylinder with the atmosphere by way of the port f⁶. When the port c becomes the inlet-port, the position of the valves J J' is reversed, so that the valve J' is closed, and the valve J then connects 20 the interior of the cylinder with the atmosphere by way of the ports f f² and f⁴ f⁶.

The exhaust-valves J J' operate in unison with the exhaust-valves J² J³ for the auxiliary or governing engine A', only in a reverse direction—that is, when the valves J J³ are open the valves J² J' are closed, and when the valves J J³ are closed the valves J' J² are open. For this purpose the following mechanism is provided, controlled by the reversing-lever J⁴, adapted to be manipulated by the operator and arranged to be engaged with a notched segment J⁵, carried by the engine A'. (See Fig. 4.) The reversing-lever J⁴ is secured on one end of the stem J⁶ of the valve 35 J³, and said lever is connected by a link J⁷ with an arm J⁸ on the stem J⁹ of the exhaust-valve J². On the stem J⁶ of the exhaust-valve J³ is also secured a bevel gear-wheel J¹⁰ in mesh with a bevel gear-wheel J¹¹, secured 40 on a shaft J¹², carrying at its lower end a bevel gear-wheel J¹³ in mesh with a bevel gear-wheel J¹⁴, secured on the stem J¹⁵ of the exhaust-valve J'. On the stem J¹⁶ is secured an arm J¹⁶, connected by a link J¹⁷ with an 45 arm J¹⁸ on the stem J¹⁹ of the reversing-valve J. It is evident that when the operator moves the reversing-lever J⁴ from a vertical normal position to either the right or the left, then the several exhaust-valves J J' J² J³ are correspondingly manipulated for running the 55 main engine A in a forward or reverse direction at the same time the auxiliary engine is run in a forward or in a reverse direction, according to the position in which the lever 60 J⁴ is moved.

The admission of the motive agent to the cylinder A³ of the governing-engine A' is essentially the same as that described in the Letters Patent above referred to—that is, the 65 motive agent passes from the end of the cylinder adjacent to the head A⁷ through a valve-seat K into a cylindrical valve L, se-

cured on the shaft D' and mounted to turn in a central bore C⁸, formed at one end of the piston C'. (See Figs. 1 and 7.) The motive 70 agent passes from the valve L past the valves N into chambers C⁹ by way of a port h, leading from the bore C⁸ to the said chambers, and the motive agent passes from each chamber C⁹ through one of two ports i or i' into the 75 cylinder at the working side of the piston-heads H⁵ H⁶, arranged diametrically opposite each other and similar in construction to the piston-heads H H', above described in reference to the engine A. The ports i i' are controlled 80 by valves O O', secured on a lever O², fulcrumed at its middle in the chamber C⁹, so that the port i or i' which is on the exhaust side of the corresponding piston-head H⁵ or H⁶ closes, while the other port is open to allow 85 the motive agent to pass to the working or pressure side of the piston-heads.

The valve-seat K is provided with a cut-out portion K', and the cylindrical cut-off valve L, rotating on the said valve-seat and 90 rigidly secured to the shaft D', is provided with two oppositely - arranged ports g g', adapted to connect alternately the cut-out portion K' of the valve-seat K with the ports h h' to allow the motive agent to pass from the 95 end of the cylinder through the cut-out portion K' and the ports g g h h' and the valves N into the chamber C⁹ at the time the valves N are open, so that the motive agent finally 100 passes from the chamber C⁹ through the open ports i or i' to the working or pressure side of the cylinder to rotate the piston C' either in a reverse or forward direction—that is, in the direction opposite to that in which the piston C is traveling. Each of the valves N 105 has its valve-stem N' journaled in suitable bearings in the piston C', and the outer ends of the said valve-stems N' adjacent to the head A⁶ are provided with crank - arms N², (see Figs. 5 and 7,) pivotally connected with the 110 eccentric-strap N³ of an eccentric disk N⁴, secured to or formed on a bracket N⁵ on the cylinder-head A⁶, as is plainly indicated in Fig. 5. It is evident that when the piston C' rotates the stems N' move with the piston, 115 and in doing so carry the eccentric-strap N³ around the fixed eccentric disk, so that a rotary motion is given by the eccentric-strap and the crank-arms N² to the valve-stems N', so as to rotate the valves N, and thereby open 120 and close the same at the proper time. The valves N serve to prevent the motive agent from pressing the piston-heads H⁵ H⁶ outward at the time the valve K is cutting off at or near zero—that is, the valves N are closed 125 from the time the piston H is in front of the port f until it is in front of the port f'—and consequently there is no pressure on the piston-heads during this time—that is, while the piston-heads are receding—and the said 130 valves also serve to balance the said piston-heads. The chamber C⁹ also connects with a chamber C¹⁰, into which projects the inner or flanged end of the corresponding piston-head

H^5 or H^6 to force the latter into an outermost position by the live steam. A spring H^3 presses on each piston-head H^5 and H^6 , the same as the spring H^3 on the piston-heads H^5 and H^6 , and this spring H^3 serves to hold the piston-head H^5 or H^6 in position to work until the motive agent begins to come through the valve N , as the latter is closed until the piston-head H^5 or H^6 is in front of the port f . The springs also serve to hold the piston-heads in proper position when the engine is running very slow. The valve L is formed at the inside with an offset L^2 to balance the valve-seat K , as steam can get under the seat and balance all of it except that portion covering the port g' .

The valve-seat K is under the control of the operator and is also controlled by the boiler-pressure, and for this purpose similar devices are employed to those shown and described in the patent above referred to, with the exception that the valve-seat K is not rigidly connected with the gear-wheel K^2 , but by a lug and notch to allow the valve-seat to take up its own wear. The gear-wheel K^2 is in mesh with a gear-wheel K^3 , secured on a shaft K^4 , connected by a gearing K^5 with a hand-wheel K^6 , under the control of the engineer for turning the hand-wheel so as to rotate the valve-seat K to move the same into proper position for running the engine A' forward or backward. A controlling device P for controlling the valve-seat K according to boiler-pressure is provided with a cylinder P' , in which reciprocates a spring-pressed piston P^2 , said cylinder P' being connected by a valved pipe P^3 with the steam-inlet pipe F^2 for the engine A' . The piston P^2 is connected by the mechanism P^4 with the shaft K^4 , and this mechanism is the same as the one described in the patent above referred to, so that further description of the same is not deemed necessary, it being understood, however, that when the boiler-pressure increases beyond a normal pressure then the piston P^2 is forced downward beyond its normal position to rotate the valve-seat K , so that the latter changes its position relatively to the cut-off valve L , according to the increase in the boiler-pressure, and consequently cut off takes place sooner on an increase of pressure, and a like result in a reverse direction takes place when the boiler-pressure decreases, as the spring on the piston P^2 then pushes the latter upward and the valve-seat K is turned in the opposite direction and changes its position relatively to that of the valve L , so that the cut off takes place later and more steam is admitted to the cylinder. The valve P^5 in the pipe P^3 is actuated from the link J^7 by the same mechanism as described in the patent above referred to, so that when it is desired to reverse the engine the cylinder P' is connected with the outer air, while steam is cut off from the cylinder to permit of conveniently reversing the engine. The controlling device for the valve-seat K is also provided

with an indicator for indicating the position of the valve-seat relatively to the cut-off valve L , and as this device is the same as that described in the patent previously referred to it is not deemed necessary to describe the same again in detail.

The yielding connection between the piston C' and the shaft D' is similar to the one described in the patent referred to—that is, it is provided with disks Q Q' , rods Q^3 , a disk Q^4 , pressed on by a spring R , and all contained in a bore C^{11} , adjacent to the bore C^8 , containing the cut-off valve L . The two disks Q Q' are loose on their shaft and are provided with friction-rollers Q^2 , engaged by projections C^{12} , extending from the wall of the bore C^{11} in an inward direction, so that when the piston is rotated the projections carry the disks along. The disks Q Q' are provided at their hubs with inwardly-projecting pins Q^5 Q^6 , adapted to engage annular grooves D^7 and spiral grooves D^8 , formed on an enlarged portion of the shaft D' , as plainly shown in Fig. 7. Now when the load on the shaft D' increases beyond a normal load, then the shaft D' drags relatively to the piston C' , and in doing so the disk Q' is caused to travel inward toward the disk Q at the time the pin Q^6 permits the piston C' to rotate to bring the piston in such relative position to the cut-off valve L that the cut-off takes place later, so as to allow more steam to pass into the cylinder and overcome the increase in the load. In case the load decreases the disk Q' moves outward by the tension of the spring R , and consequently said disk tends to turn the piston C' faster to reduce the amount of steam passing into the cylinder. In either case the spring tends to equalize the discrepancy between the pressure of the steam in the cylinder and the load connected with the shaft D' , so that the disk Q' moves correspondingly, and consequently the admission of steam to the cylinder and piston is governed according to and from the load by way of the shaft D' . When the engine is reversed, the action is the same as above described, the only difference being that it is the disk Q that moves toward or from the other disk, Q' , but against the tension of the spring R , for the purpose set forth.

In order to indicate the horse-power of the engine, the following device is provided, reference being had to Fig. 1: On the outer end of the shaft E^2 for the upper cut-off valve E' is arranged a sleeve S , having an annular groove S' engaged by a pin on a pointer S^2 , fulcrumed on a suitable bracket carried by the steam-chest F , the pointer on a graduation S^3 indicating horse-power from zero upward, both when the engine runs in a forward direction and when it is reversed. On the sleeve S is secured a gear-wheel S^4 , in mesh with a gear-wheel S^5 , secured on the shaft D' adjacent to the bevel gear-wheel D^2 , and on the hub of the gear-wheel S^4 is secured a pin S^6 , extending into a spiral slot S^7 , formed on one end of the shaft E^2 . The rotary mo-

tion of the shaft D' is transmitted by the gear-wheel S⁵ to the gear-wheel S⁴ and the sleeve S, and when the shafts D' and E² travel at a different rate of speed it is evident that 5 the sleeve S is caused to slide on the shaft E², owing to the pin S⁶ engaging the spiral groove S⁷, so that the shifting of the sleeve on the shaft causes the pointer S² to swing to indicate the horse-power.

10 In order to counterbalance the piston-heads H H' in the piston C, the following device is provided, reference being had to Figs. 1 and 8: On the outer faces of the ends of the piston B are secured or formed the oppositely-arranged guideways T, formed at their inner parallel edges with grooves T' for receiving the opposite sides of a block T², formed with an elongated slot T³ for the free passage of the shaft D, and on the said block are pivoted 15 the shoes T⁴, engaging cam rings or grooves T⁵, formed on the inside of the cylinder-heads A⁴ A⁵. Now when the piston B rotates the block T² is shifted in its guideways T by the action of the shoes T⁴ traveling in the cam-grooves T⁵, so that the piston-heads H H' are counterbalanced to insure an easy uniform running of the piston in the cylinder A² without jerk or jar.

20 To permit the removal of the shoes T⁴ for repairs or otherwise without removing the cylinder-heads A⁴ A⁵, holes larger than and of the shape of the shoes are formed in the said heads and leading into the cam-grooves T⁵, and said openings are closed by plates x, carrying 25 plugs fitting said openings, as clearly shown in Figs. 1 and 4.

The packings B B' in the cylinders A² and A³ are alike in construction, and each consists of four chambered blocks B² B³ B⁴ B⁵, (see 30 Figs. 9, 10, 11, and 12,) the blocks B² B³ having tongues and recesses 1 and 2 on each side and pressed apart by a spring B⁷, surrounding a rod 3, having bearing in blocks 4 in the chamber of the blocks B² B³, and the blocks 35 B⁴ B⁵ are similarly arranged and pressed apart by a spring B⁸. The sets of blocks B² B³ and B⁴ B⁵ are pressed apart in a radial direction by a spring B⁹, and the side flanges B⁶ of the set of blocks B⁴ B⁵ are provided with side 40 flanges B⁶, extending from opposite faces and overlapping a portion of the sides of the set of blocks B² B³. By the arrangement described the blocks are pressed outward and fit snugly against the inside of the annular flanges C¹² of the pistons C C' and radially to make tight contact with the peripheral surface of the pistons between their flanges C¹³.

The packings H⁴ for the piston-heads H, H', H⁵, and H⁶ are alike in construction, and each 45 consists of two longitudinally-extending bars H⁷, overlapping each other at their inner ends and carrying at their outer ends spring-pressed heads H⁸, fitting into recesses at the inner faces of the flanges C¹³. (See Fig. 1.) The 50 bars H⁷ are mounted to slide radially on pins H⁹, carried by the piston-head and extending through elongated grooves in the said bars.

(See Fig. 7.) The bars are pressed at their under sides by the free end of a spring H¹⁰ to hold the outer faces of the bars in contact 70 with the inner surface of the cylinder A² or A³. The tops of the bars are provided with transverse arms H¹¹, fitting into corresponding recesses in the piston-head, and the said arms H¹¹ slide under partitions in the ports 75 f f' to allow the packings H⁴ to readily pass the said ports. (See top of Fig. 7.) The inner overlapping ends of the bars are pivotally connected to insure a uniform simultaneous movement of both bars and a consequent 80 even wear thereof.

The flanges C¹³ of the pistons C C' engage with their peripheral faces packing-rings U, set in annular recesses in the cylinders A² A³, respectively, to prevent leakage of the motive 85 agent from the cylinder past the said flanges.

The pipe F⁹, connected with the motive-agent supply, (see Fig. 4,) opens into the cylinder-head A⁶ to fill the latter with steam the same as the other cylinder-head, A⁷. A port 90 k connects with a channel l in each of the exhaust-valves J² J³ to conduct the motive agent through a port n into the cylinder.

The operation is as follows: When the engines are at rest, the cut-off valve E' is closed 95 at the time the piston C is at the commencement of its working travel. When steam is simultaneously admitted to both engines, then the engines are ready to be started, the reversing-lever J⁴ being then in the center 100 notch of the segment J⁵, so that no steam is yet admitted through the valves of either engine. Now by the operator throwing the lever J⁴ partly over to one side and admitting steam to the controlling-engine A' then the 105 piston C' is caused to rotate in the cylinder A² against the tension of the spring R. As the positive valve E is secured to the shaft D' and always commences to open at the same time that the piston-heads H and H' commence 110 their working travel, and the shaft D' is in solid connection with the main engine-shaft D, it is evident that said valve E will remain stationary until the gear-wheel G², which turns with the piston C', rotates the pinions 115 G' and the gear-wheels G⁵ G⁶ in a reverse direction and with them the valve E' until the latter is sufficiently open for the admitted steam to overcome the load on the main shaft D. It is understood that the cut-off valve E' when working at zero is always 120 just closing as the other and positive valve E is just opening. The reason for having the gear-wheel G⁵ and the pinions G' loose on their shafts is to cause a retarding motion 125 on the cut-off valve E'—that is, the bracket G⁴, secured on the piston C', gains on the shaft D'; but the gaining motion is turned into a losing motion, so far as the valve E' is concerned, by the small pinions G', thereby 130 prolonging the cut-off when the load is thrown on. The head G, on which the pinions G' are mounted to revolve loosely, is fastened with a set-screw to the shaft D', thereby carrying

130

the said pinions G' around to cause the gear-wheels G^5 and G^6 to go with it, the only variation between the bracket G^4 and the gear-wheels G^5 G^6 being what the tension of the 5 spring R allows. As above explained, the amount of tension given to the spring R is indicated by the pointer S^2 on the graduation S^3 as the sleeve S is caused to slide on the shaft E^2 according to the variation of 10 part of a revolution in the speed between the shafts E^2 and D' . The reason for the lever J^4 being but partly thrown over, as previously mentioned, is to allow steam to pass into the piston C' to start the auxiliary engine. This 15 is done by the exhaust-valves J^2 J^3 making connection at the channels l with the ports k and n , so that steam from the head A^6 can pass by way of said ports and channels into the engine-cylinder and behind the piston-head H^5 or H^6 to start the piston in the direction of the arrow d^2 . When the lever J^4 is thrown over sufficiently to allow a partial opening of the exhaust-valves J^2 and J^3 , then 20 the channel l in the corresponding valve connects the said ports, as above described, and when steam has moved against the piston-head H^5 or H^6 and against the tension of the spring R sufficiently to uncover the port h then the lever J^4 can be thrown completely 25 over and the ports k and n and the channel l in the valve J^2 or J^3 will now be disconnected and shut off. When the lever J^4 is in its middle position and the valve-seat K is indicated centrally, then both exhaust and inlet 30 are closed on both engines by the gearing J^{11} J^{18} . Therefore the piston C' , being inactive, brings the cut-off valve E' to cut-off (or closed) position just as the positive valve E is coming open, and the engines cannot get steam. 35 Therefore the ports a and b are not open both at once in any position of revolution when the lever J^4 is in the middle position; but when the lever J^4 is in either of its outer notches then the engines are working and the 40 port a on the cut-off valve E' will stand in relation to the port b on the positive valve, the variation caused by load causing cut-off valve E' to drag through the spur-wheels G G' . Each port a and b , also a' and b' , (acting in pairs,) is in operation for one half-revolution of the main engine and then turns over and acts on another half-revolution of the main engine before getting back to the first 45 position. For instance, if the ports a and b act on the piston-head H' when the piston H gets around to exhaust then the ports a and b will be closed and the other pair, a' and b' , will act on the piston-head H' in like manner. This is the reason why an auxiliary engine only revolves once for the main engine 50 revolving twice.

Between the inner disk Q of the yielding connection and the adjacent cut-off valve L is arranged a bearing-disk L^3 to carry the piston C' centrally, and thereby prevent the said valve L from coming in frictional contact with its chamber.

By having a double engine, as described, the greater part of the power is thrown upon a shaft connected to a piston, so that in case 70 of a large double engine the strain is not thrown on the yielding spring connection any more than is sufficient to govern both engines.

Having thus fully described my invention, I claim as new and desire to secure by Letters 75 Patent—

1. The combination with a main rotary engine and an admission-valve operated thereby, of a controlling-engine for controlling the main-engine admission-valve, the controlling-engine consisting of a rotary engine geared with said valve, substantially as shown and described. 80

2. The combination with a main rotary engine, of a controlling-engine for controlling 85 the main-engine admission-valve, said controlling-engine comprising a revoluble piston in a cylinder, and a yielding connection between said piston and said valve, substantially as shown and described. 90

3. The combination, with a main rotary engine having a piston fast on the main shaft, of an auxiliary or controlling rotary engine having its shaft geared to the main shaft and 95 yieldingly connected with its piston, substantially as shown and described.

4. The combination, with a main rotary engine having a piston fast on the main shaft, of an auxiliary or controlling rotary engine having its shaft geared to the main shaft and 100 yieldingly connected with its piston, the yielding connection controlling the admission-valve of the main engine, substantially as shown and described.

5. The combination with a main rotary engine having two admission-valves, one of 105 which is positively actuated from the main shaft, of an auxiliary rotary engine having a yielding connection between its piston and shaft, the latter being directly geared to the 110 shaft of the main engine, and the yielding connection controlling the second admission-valve of the main engine, substantially as shown and described.

6. A rotary engine, provided with a piston, 115 a piston-head slidable in said piston, and having a packing comprising spring-pressed bars slidable radially in the piston-head, and spring-pressed caps on the ends of the bars and fitting into recesses in the piston-flanges, 120 the inner overlapping ends of the said bars being pivotally connected with each other to cause the bars to yield in unison, substantially as shown and described.

7. A rotary engine, provided with a piston, 125 a piston-head slidable in said piston, and having a packing comprising spring-pressed bars slidable radially in the piston-head, spring-pressed caps on the ends of the bars and fitting into recesses in the piston-flanges, and 130 transverse guide-arms on the tops of the bars, and fitting into recesses in the piston-heads, substantially as shown and described.

8. A rotary engine, provided with a cylinder

drical piston containing valves covering ports exposed to the atmosphere, said ports also acting as feed-ports and also as relief-ports for the piston-heads; said ports also acting to prevent vacuum and compression, substantially as shown and described.

9. A rotary engine, provided with a cylindrical piston containing a rotating valve to prevent pressure on the piston-heads while the latter are receding from the cylinder-abutments, said valve also acting to balance said piston-heads, substantially as shown and described.

10. A rotary engine, provided with a cylindrical piston containing a rotating valve to prevent pressure on the piston-heads while the latter are receding from the cylinder-abutments, said valve also acting to balance said piston-heads, and means, substantially as described, for actuating the said valve from the piston when the latter rotates, substantially as shown and described.

11. A rotary engine, provided with a cylindrical piston containing a rotating valve to prevent pressure on the piston-heads while the latter are receding from the cylinder-abutments, said valve also acting to balance said piston-heads, a stationary eccentric-disk, an eccentric-strap, and a crank-arm on the stem of the said valve to rotate the latter when the piston is rotated, substantially as shown and described.

12. A rotary engine provided with an abutment-packing, comprising four chambered blocks arranged in pairs, the blocks of each pair being provided with engaging tongues and recesses and pressed apart by a spring in the chambers thereof, one pair of blocks being provided with side flanges overlapping the blocks of the other pair, the pairs of blocks being pressed apart by a spring, substantially as described.

13. A rotary engine provided with an abutment-packing, comprising four blocks arranged in pairs pressed apart by a spring, the blocks of each pair being chambered and provided with engaging tongues and recesses, bearing-blocks in the chambers, a rod engaging the said blocks, and a spring surrounding the rod, substantially as described.

14. A rotary engine provided with an abutment-packing, consisting of four chambered blocks arranged in pairs, the pairs being pressed apart by a spring, each pair being provided with engaging tongues and recesses and one pair with side flanges overlapping the other pair, the blocks of each pair containing a bearing-block in its chamber, with which a rod surrounded by a spring engages, substantially as described.

15. A rotary engine, provided with a positively-driven admission-valve, a cut-off valve, and a yielding connection between said valves, substantially as shown and described.

16. A rotary engine provided with a valve actuated positively by action of a solid gearing with main shaft of engine, and a valve actuated variably by a yielding connection between the governor mechanism and main shaft, said yielding connection comprising pinions journaled loosely on a head on the positive-valve shaft, and gear-wheels in mesh with opposite sides of said pinions, one of the gear-wheels being fastened to positive-valve shaft and the other connected to and varied by motive power acting on a piston connected by a spring to positive-valve shaft, substantially as described.

17. A rotary engine provided with a rotary positive valve, and a rotary variable valve, each valve having two ports passing centrally through the valves with a partition between, the ports being at right angles to each other, substantially as described.

18. A rotary engine, provided with a piston, piston-heads slideable therein, and a counter-balancing device for said piston-heads, the said device comprising a fixed eccentric-ring, shoes sliding in the ring, and a block slideable on the said piston and carrying the said shoes, substantially as shown and described.

19. A rotary engine, provided with a piston, piston-heads slideable therein, a counterbalancing device for said piston-heads, the said device comprising a fixed greater half of a cam ring or groove and a lesser half of a true-circle ring or groove, shoes sliding in said portions of the true and cam groove, a block slideable on the said piston and carrying the said shoes, and means whereby the shoes may be readily applied or removed, substantially as shown and described.

20. A rotary engine, provided with a means for automatically starting the engine, the means comprising a reversing exhaust-valve having a channel at one end, and ports through the cylinder, to admit steam through the ports and channel to the cylinder in advance of the regular steam-inlet, substantially as shown and described.

21. A rotary engine, provided with a power-indicator, comprising a loose gear-wheel on the cut-off-valve shaft and in mesh with a gear on the positively-driven admission-valve shaft, the loose gear-wheel having a pin engaging a spiral groove in the cut-off-valve shaft, a yielding connection between the shafts of the said valves and a pointer engaged by the hub of the said loose gear-wheel, substantially as shown and described.

In testimony whereof I have signed my name to this specification in the presence of two subscribing witnesses.

THOMAS CROSTON.
